(57) **CLAIM**

The ornamental design for a flotation article, as shown and described.

DESCRIPTION

FIG. 1 is a front, top and left-side-perspective view of a first embodiment of a flotation article;
FIG. 2 is a front-elevational view thereof;
FIG. 3 is a rear-elevational view thereof;
FIG. 4 is a left side-elevational view thereof;
FIG. 5 is a right-side-elevational view thereof;
FIG. 6 is a top-plan view thereof; and,
FIG. 7 is a bottom-plan view thereof.

The broken lines shown in the drawings are shown for illustrative purposes only and form no part of the claimed design.
